COMBINED DISPLAY AND STORAGE STAND FOR WIRE CORD OR THE LIKE

Anthony M. Chiarello, 1617 W. 206th St., Torrance,
Calif. 90501, and Frank J. La Marca, 1510 W.
187th St., Gardena, Calif. 90247

Filed Feb. 19, 1968, Ser. No. 10,633

Term of patent 14 years

Int. Cl. D6—01

U.S. Cl. D80—9

The figure is a perspective view of a combined display and storage stand for wire cord or the like showing the new design, a portion being broken away for convenience of illustration.

We claim:

The ornamental design for a combined display and storage stand for wire cord or the like, substantially as shown.
